UNITED STATES PATENT OFFICE.

GEORGE W. ST. JOHN AND DE VALOIS ST. JOHN, OF LEONARDSVILLE, N. Y.

HAY ELEVATOR AND CARRIER.

SPECIFICATION forming part of Letters Patent No. 247,586, dated September 27, 1881.

Application filed March 14, 1880. (No model.)

To all whom it may concern:

Be it known that we, GEORGE W. ST. JOHN and DE VALOIS ST. JOHN, citizens of the United States, residing at Leonardsville, in the 5 county of Madison and State of New York, have invented certain new and useful Improvements in Hay-Elevators, of which the following is a specification.

Our invention relates to improvements in 10 that class of hoisting and carrying devices commonly known as "hay-elevators;" and it consists, first, in the mode of supporting the rail, or track; and, second, in improvements in the construction of the traveling carriage and parts 15 connected therewith, and in the construction of the bail for supporting the load.

According to our invention, we suspend a 20 bar of iron, by preference round, and of five-eighths ($\frac{5}{8}$) of an inch diameter along the building, well up in the peak of the rafters. This rod we term a "rail-rod." It serves as the railway for the traversing carriage, and is supported at the driveways by means of pairs of 25 hooks or supports so constructed that when it is desired that the traversing carriage shall pass from any given point in the building in excess of the distance between one pair of hooks to another the rail-rod can be slipped out of any pair of the hooks or supports and 30 allowed to sag, thereby enabling the traversing carriage to pass such point without interruption or removal from the rail-rod. The 35 hooks or supports are arranged in pairs, one on each side of the rafters or supports to which they are attached, one of each pair being right and the other left handed, so that either one or other of the pair may be in position to operate on one or other of the catches carried by the traveling carriage, hereinafter more fully 40 described, according to the direction in which the carriage is traveling. The alternate pairs of hooks or supports carrying the rail-rod between the two end bearings for the same are placed two inches or more out of the vertical 45 and horizontal line. When the rod is lifted out of any pair or series of pairs of hooks or supports it settles and moves laterally, so as to allow the car to travel the entire length of the building.

The carriage is provided with a main framing, having two or more pulleys or wheels mounted therein adapted to run on the rail-rod. At each end the carriage is provided with spring-lever catches mounted in suitable bearings, adapted to engage with peculiarly-formed 50 openings in the hooks or supports carrying the rail-rod. These catches are automatically operated by the upper portion of the bail of the hay or other fork, first, to open the catches, and secondly, by a curved bar or extension arranged 55 near the center thereof to disconnect the catch for the time in operation and allow the carriage to be traversed the desired distance along the building. The carriage at each end is provided with a projection, having a projecting 60 collar or extension adapted to retain suitable loops or holders. The loop applied to the extension of the carriage at one end has the end of the hauling and lifting rope attached thereto, while the opposite extension supports a pulley, over which the hauling and lifting rope 65 passes.

The hay-fork or other lifting means is attached to the bail by means of bars or rods, between which is mounted a pulley-wheel adapted 70 to run upon the lifting and hauling rope. Curved guides conduct the bail into proper position, and springs are employed to keep the latches in a locked position, except when being actuated by the bail.

The accompanying drawings form a part of 75 this specification, and represent what we consider the best means of carrying out the invention.

Figure 1 represents a side view of the complete device at the end of its travel and in position for loading. Fig. 2 is a plan view of the same. Fig. 3 is a central vertical section. Fig. 4 is a perspective view of a portion of the levers and their upper guides. Fig. 5 is a detached view of the end of one of the catches, and Fig. 6 is a full-sized view of one of the hooks or supports carrying the rail-rod.

Similar letters of reference indicate corresponding parts in all the figures.

A represents the rail or track, which is supported by means of a series of pairs of hooks or supports, B, provided with projections b',

adapted to be driven into the rafters or supports, (part of one of which is shown at C, Figs. 1 and 6,) and also with a suitable hole for the reception of a screw or bolt, *b*, for the further securing of the hooks *B* in position. Inclined curved openings *B'* are formed in the lower part of the hooks or supports *B*, for engaging with the catches of the carriage *D*, for the purpose of locking the carriage in position for loading.

The carriage *D* is composed of a pair of curved bars, *d d*, provided with cross-bars *d' d'*. *E E* are pulleys or wheels mounted on axes *e e*, carried by the bars *d d*, and which, by running on the rod *A*, serve to support the carriage *D*.

F F' are levers pivoted at *ff* to the opposite ends of the carriage *D*. These levers, at one end, are provided with catches *f' f'*, while at the opposite ends, *f'' f''*, they are so formed as to interlock for the purpose of simultaneous action. One of the ends *f''*, being formed with a catch, *f''*, is adapted to engage with and hold the bail and carry the load held by the hay-fork or other engaging means. (Not shown.) *d'' d''* are springs carried by a bracket, *d'*, extending out from the cross-bar *d'*. These springs serve to keep the levers *F F'* in a right line, or nearly so, with the catch *f''* bearing against the curved guide *d''*, carried by the cross-bar *d'*.

G G are curved projections carried by the cross-bar *d'*, and adapted to guide the bail correctly into position and prevent its being raised too high.

H is the hauling and lifting rope. This rope at one end is connected to a loop, *H'*, adapted to be readily applied to or removed from one or other of the extensions *I*, formed on or applied to the opposite ends of the carriage *D*. These projections *I* are provided with projecting collars *i*. The rope *H* then passes under the pulley *K*, carried by the rods *K'*, supporting the hay-fork. The rope then passes up over a pulley, *L*, carried by a loop, *L'*, supported on the extension *I* at the opposite end of the carriage *D*.

K'' is the bail which supports the rods *K'*. This bail is loop-formed, and is provided with a curved cross-piece, *k*.

The operation of the device is as follows: Supposing the parts to be in the position shown by Fig. 1, in which the carriage *D* is represented as over a driveway, with its parts in the position they will assume when raising a load. The bail *K''* is now raised by drawing on the rope *H* sufficiently to cause the pulley *K* to raise the rods *K'* and the bail with its load to a height such that the cross-piece *k* of the bail *K''* shall come between the catch *f''* of the lever *F'* and the guide *d''*, thereby throwing back the levers *F F'* and disengaging the catch *f'*, for the time in engagement with a hook, *B*. The carriage *D* is then free to be drawn along the rod *A* to the required distance. This move-

ment is effected by pulling on the rope *H* and drawing it and the carriage in the direction of the arrow 1, Fig. 1, until it has carried its load to the desired position, when the same will be dumped by pulling the ordinary discharging rope of the hay-fork or holding device. The rope *H* is then slightly slackened, so as to allow the loop of the bail *K''* to rest on the catch *f''*, where it will remain until the carriage *D* has been drawn back the required distance, so that the hook *f''* of the lever *F* will engage with the opening *B'* of a hook, *B*, and disengage the bail *K''* from the hook *f''*, thereby allowing the bail and its attachments to descend and receive a fresh load on the slackening of the rope *H*. Immediately the bail *K''* has passed the catch *f''* the levers *F F'* will be forced into a right line by the springs *d''*, thereby locking the carriage *D* in position to receive a load. The hooks *B*, for supporting the rods *A*, as shown by Fig. 6, are formed with a recess, *b'*, for the reception of the rods *A*, and with a projection, *b*, which prevents the same from slipping out accidentally. The hooks *B* are applied to the rafters *C* in pairs, formed right and left handed, in an angular position, for the purpose of facilitating the lifting of the rod *A* out of the recess *b'* of any one or more of a series of hooks, *B*, when it is desired to pass by any one or more hooks *B* before loading or unloading.

It will be readily seen that the carriage *D* may be worked in either direction on the rod *A* by simply disengaging the loops *H' L'* from the extensions *I* and reversing their position end for end, and operating the dump-rope in the opposite direction.

Modifications may be made of the invention.

In place of employing a pair of hooks, *B*, we can employ a double-sided hook adapted to operate on either of the catches *f* or *f'*, according to the direction in which the carriage *D* is traveling.

In place of employing a pair of springs, *d''*, the same may be one continuous piece; or in some cases we can employ one or more springs of a different character to those shown, so long as the same act on one or both of the levers *F F'*, tending to keep the same in line.

We claim as our invention—

1. The combination, with the carriage *D*, of the levers *F F'* and springs *d'' d''*, arranged and constructed substantially as and for the purpose shown and described.

2. The combination, with a rod, *A*, and a series of hooks, *B*, constructed and supported as described, of the carriage *D*, levers *F F'*, and springs *d'' d''*, arranged and constructed substantially as set forth.

3. The combination, with a carriage, *D*, and automatic engaging and disengaging levers *F F'*, of the bail *K'' k*, constructed and adapted to operate substantially as described.

4. The combination, with a carriage, *D*, pro-

120

125

130

vided with guides G G d^4 d^5 , and levers F F', of the bail K² k, constructed and adapted to operate substantially as set forth.

5. The combination, with a carriage, D, provided with automatic devices for holding and disengaging a bail, K², of the extensions I i and loops H' L', pulleys K L, and rope H, substantially as set forth.

In testimony whereof we have hereunto set

our hands, at Leonardsville, Madison county, 10 New York, this 28th day of February, 1881, in the presence of two subscribing witnesses.
